UNITED STATES PATENT OFFICE.

JOHN M. HOPWOOD, OF DORMONT, AND BRYANT BANNISTER, OF PITTSBURGH, PENNSYLVANIA, ASSIGNEES TO GEORGE J. HAGAN, TRUSTEE, OF PERRYSVILLE, PENNSYLVANIA.

PUMP.

Application filed November 19, 1921. Serial No. 516,392.

To all whom it may concern:

Be it known that we, JOHN M. HOPWOOD and BRYANT BANNISTER, residing at Dormont and Pittsburgh, respectively, in the county of Allegheny and State of Pennsylvania, citizens of the United States, have invented or discovered certain new and useful Improvements in Pumps, of which improvements the following is a specification.

10 The invention described herein relates to an improvement in pumps employed for effecting a circulation of liquids as for example for causing the flow of water from a boiler through a filter or other water treating device and back to the boiler; and the invention has for its object a construction wherein the liquid moving piston is shifted in one direction by the pressure of the liquid to be moved and in the opposite direction by the conjoint action of such pressure and the pressure of steam or other fluid under pressure. The invention is hereinafter more fully described and claimed.

15 In the accompanying drawings forming a part of this specification, Fig. 1 is a sectional elevation showing the improved pump operatively connected to a filter; Fig. 2 is an enlarged sectional view of the controlling valve; Fig. 3 is a sectional view 20 on an enlarged scale of the valve mechanism controlling the admission of steam; Fig. 4 is a sectional detail of the lower end of the pump showing inlet and outlet ports and valve for the lower end of the pump; Fig. 4 is a plan view of the lower head 25 of the pump, and Fig. 5 is a sectional development of the lower head.

25 The pump consists of a cylinder 1 in which is arranged the piston 2. The valves controlling the flow of water to and from the cylinder are located in the head 3 secured to the lower end of the cylinder. Two of the valves, 4 and 5, control respectively the inlet and outlet for the lower 30 end of the cylinder, while the inlet and outlet for the upper end of the cylinder are controlled by the valves 6 and 7, said inlet and outlet being connected by passages 8 and 9 to the upper end of the cylinder. The inlets 4 and 6 are connected by passages 10 in the head to a port connected by a pipe 11 to the discharge from the filter or other treating apparatus and the outlet ports 5 and 7 are connected by passages 12 to a port which is connected by a pipe 13 to the boiler or other receptacle.

35 The inlet to the filter is connected to the boiler and hence as the filter will present little resistance to the passage of water therethrough unless the filter is greatly fouled, the pressure of the liquid per square inch of area will be substantially the same on both sides of the piston. The area of the underside of the piston is proportional to the diameter, but the area of the upper surface exposed to the pressure of the water is proportioned to the diameter of the piston minus the cross sectional area of the piston rod 14 which is preferably made of a diameter greater than necessary for structural purposes, thus ensuring a greater differential between effective pressures on opposite sides of the piston.

40 The piston rod 14 extends up in the cylinder 15 and is connected by the piston 16 located therein. This cylinder and piston are made of such diameters that the pressure of steam on its upper surface plus the pressure of water on the upper surface of the pump piston will be sufficient to overcome the pressure on the underside of the pump area and force the piston down.

45 The flow of steam to and from the cylinder 15 is controlled by a valve 17 and a piston valve 18 connected by a stem 19, the seats for said valves being formed at the ends of a bushing 20 secured in the valve chest 21 and connected at a point intermediate its ends to the cylinder 15 by a port 22. Steam is admitted to the valve chest through a port 23 located above the bushing. In order to hold the inlet valve in open position and the piston or outlet valve 18 in closed position, a passage 24 is formed through the piston valve 18 permitting of the flow of steam from the chamber in the bushing to the chamber 25 below the piston valve. As the effective area of the lower end of the piston is larger than that of the upper end the pressure of steam in the chamber 25 will keep the exhaust valve closed and the inlet valve open. The shifting of these valves to permit of the flow of steam to and from the cylinder is effected by the pump piston through a rod 26 which is connected at its upper end to the valves and passes

21 down through the pump piston. Tappets 27 are secured on this rod at such points that the piston will strike such tappets and shift the rod and valves as it approaches 5 the ends of its stroke.

It is preferred to include resilient element 28 in the valve rod 26 and to so set the tappets 27 that the resilient element will be placed under increasing tension as the 10 pump piston approaches the limits of its movements and that such tension will become sufficient to overcome the lock pressure of the steam on the valve, 17, or piston 18 before or as the pump reaches the end 15 of its stroke. The initial movement of the valve and piston will permit such a flow of steam as to tend to balance the valve and piston and hence the energy stored in the resilient element will be free to operate 20 and complete the movement of the valve and piston.

In describing the operation of the pump it will be supposed that the pump and steam pistons are at the upper limits of their 25 movement, and the inlet valve 17 open and exhaust valve 18 closed. The pressure of the steam on the piston 16 will cause the pump piston to move down forcing water through the valve 5 and pipe 13 to the 30 boiler and at the same time water will flow from the filter through pipe 11 inlet valves 6 and passage 8 to the upper end of the cylinder. As steam flows through the bushing in the valve it will also flow through passage 24 to the underside of the piston valve 18 thereby holding such valve closed and the 35 inlet valve 17 open until sufficient force is applied by the pump piston as it approaches the lower limit of its movement to shift the 40 valves against the pressure of the steam, the exhaust valve to open position and the inlet valve to closed position. As soon as the steam piston is relieved of pressure the pressure of the water acting on the lower side 45 of the pump piston will move the latter up. This upward movement of the pump piston forces water down through passage 9 valve 7 and pipe 13 to the boiler and at the same time water will flow from the filter through 50 pipe 11 and port 6 into the lower end of the pump cylinder. During this upward movement of the pump piston the steam inlet valve 17 and the exhaust or piston valve 18 are held in closed and open positions respectively by the pressure of steam on the inlet 55 valve until the pump piston strikes the upper tappet and reverses the positions of these valves.

It is characteristic of this improvement 60 described herein that the features of both a single acting and a double acting pump are embodied, steam pressure being employed for moving the pump piston in one direction and the fluid operated on being 65 employed for moving the piston in the op-

posite direction. It is also characteristic of the improvement that the valve mechanism controlling the flow of steam to and from the power cylinder is shifted by the pump piston but is locked in the positions to 70 which it is shifted by steam pressure.

A further characteristic of the improvement is that all the pump valves are arranged in the lower head and readily accessible for renewal or repair, and if a duplicate be at hand, the operation of the pump need be discontinued only long enough to remove the one head and secure the other in position.

We claim herein as our invention:

1. A pump having in combination a cylinder, valves controlling the flow of fluid to and from said cylinder, a piston having an area at one end or side substantially greater than that of the other end or side and means operating intermittently in the same direction as the pressure acting on the end of the piston having the smaller area to overcome the pressure acting on the other side or end of the piston. 80

2. A pump having in combination a cylinder, valves controlling the flow of fluid to and from the said cylinder, a piston having an area at one end or side substantially greater than that of the other end or side and means controlled by and operating intermittently in the same direction as the pressure acting on the end of the piston, having the smaller area to overcome the pressure acting on the other side or end of the piston. 90

3. A pump having in combination a cylinder, valves controlling the flow of fluid to and from the cylinder, a second cylinder having its axis coincident with the first cylinder, pistons having a common piston rod arranged in said cylinders, the effective area of one side or end of the piston in the pump cylinder being greater than that of the other side or end, and a valve mechanism controlling the flow of fluid under pressure to one end of the second cylinder. 105

4. A pump having in combination a cylinder, valves controlling the flow of fluid to and from the cylinder, a second cylinder having its axis coincident with the first cylinder, pistons having a common piston rod arranged in the cylinder, the effective area of one side or end of the piston in the pump cylinder being greater than that of the other side or end, a valve mechanism controlling the flow of fluid under pressure to one end of the second cylinder, and means operative by the piston in the first or pump cylinder for shifting said valve mechanism. 115

5. A pump having in combination a cylinder, valves controlling the flow of fluid to and from the cylinder, a second cylinder having its axis coincident with the first cylinder, pistons having a common piston rod 120

arranged in the cylinder, the effective area of one side or end of the piston in the pump cylinder being greater than that of the other side or end, a valve mechanism controlling the admission of fluid under pressure to the second cylinder, and adapted to be held in admission and exhaust positions by fluid under pressure, and means operative by the piston in the first or pump cylinder for shifting the valve mechanism against such fluid pressure.

6. A pump having in combination a cylinder, valves controlling the flow of fluid to and from the cylinder, a second cylinder having its axis coincident with the first cylinder, pistons having a common piston

rod arranged in the cylinder, the effective area of one side or end of the piston in the pump cylinder being greater than that of the other side or end, a valve mechanism 20 controlling the admission of fluid under pressure to the second cylinder and adapted to be held in admission and exhaust positions by fluid under pressure, and means including a resilient member and operative by 25 the piston in the first or pump cylinder for shifting the valve mechanism against such fluid pressure.

In testimony whereof, we have hereunto set our hands.

JOHN M. HOPWOOD.
BRYANT BANNISTER.
